SADIRON HOLDER

Filed April 13, 1927

Inventor
Russell A. Winter
By Fred J. Ulrich
his Atty.

UNITED STATES PATENT OFFICE

RUSSELL A. WINTERS, OF CHICAGO, ILLINOIS

SADIRON HOLDER

Application filed April 13, 1927. Serial No. 183,283.

The invention relates to sad-iron holders and more particularly to that type which is adapted to be secured or applied to a wall structure and to support an iron which is not in use.

One object of the present invention is to provide a sad-iron holder which is of new and improved construction.

Another object of the invention is to provide a holder which is formed of bent strips of wire and embodies new and improved means for securing the iron in place. In general this means consists of a socket for receiving the heel stand of the iron and a 15 slidable spring pressed grip for hooking around the toe of the iron.

Other objects of the invention will appear hereafter from the detailed description.

The invention consists in the several novel 20 features hereinafter set forth and more particularly defined by claims at the conclusion hereof.

In the drawing: Fig. 1 is a perspective of a holder embodying the invention. Fig. 2 25 is a longitudinal section. Fig. 3 is a section taken on line 3—3 of Fig. 2.

The holder is adapted to extend in a substantially vertical position and be secured to a wall structure, and serves to retain a sad- 30 iron which is not in use. The holder consists of an outer vertically extending frame A against which the sole or base plate of the iron is adapted to lean; an inner vertically extending frame B which is connected to frame A; a horizontally extending member C which is connected to the lower end of the outer frame and forms a support upon which the heel of the iron is adapted to rest; a clip D which connects the upper ends of frames 35 A and B together; a member E which is slidably mounted in clip D and is adapted to hook around the toe of the iron, to secure the latter in place on the holder; and a spring F which is adapted to yieldingly hold member E in its hooked position.

The outer frame A is formed of a strip a of wire. The ends of the latter are bent upwardly and inwardly to form the sides a¹ of the frame and then downwardly to form 50 substantially parallel portions a². The cen-

tral portion of strip a extends horizontally and forms the bottom a³ of frame A. The inner frame B is formed of a strip b of wire, the central portion of which is bent to form a vertically extending loop b¹. The ends of strip b extend side-by-side and are bent to 55 extend horizontally and form a single leg b² for supporting the upper end of the holder. From leg b² the ends of strip b are bent downwardly to form portions b³ which extend between the portions a² of strip a; then outwardly and horizontally to form portions b⁴; then downwardly to form portions b⁵; and then inwardly to form portions b⁶ which are spot welded or soldered, as at b⁷, to the 60 bottom a³ of frame A. Member C is formed of a strip c of wire. The central portion of the latter extends outwardly of frame A and B and substantially parallel to bottom a³ and forms a support c¹ for the heel of the 65 iron. The ends of strip c are bent so as to extend at right angles to support c¹ and form legs c² for supporting the lower end of the holder. The free ends of the legs c² are bent to form vertically extending loops c³. The 70 central portions of legs c² are spot welded or soldered, as at c⁴, to the ends of bottom a³. The space between the legs, support c¹ and bottom a³ constitutes a socket which is 75 adapted to receive the heel stand (shown in dotted lines, Fig. 2) of the iron and to hold the heel end of the iron against displacement. Clip D is in the form of a flattened ring d and extends around and is soldered or spot welded to portions a² and the upper ends of 80 portions b³ to secure the upper ends of frames A and B together. Member E is formed from a strip e of wire. The central portion of the latter extends horizontally and is bent 85 to form a semicircular portion e¹ which extends beneath the portions b³ of strip b. The ends of strip e are bent upwardly to form portions e² which extend parallel to and between portions a² and b³, and then horizontally to form oppositely facing hooks e³ 90 which are adapted to hook around the toe end of the sole of the iron. Portions e² are slidably in ring d so that member E may be shifted longitudinally to fit irons of different lengths. Spring F is formed of a coil of 100

wire f and is applied to resiliently hold member E in its hooked position. One end f^1 of the spring extends around the semicircular portion e^1 of member E and the other end f^2 extends around a hook b^8 which is integrally formed on one of the portions b^6 of frame B.

The legs of the holder are of sufficient length to prevent the transfer of heat from the iron to the wall structure to which the holder is secured. Leg b^2 is shorter than leg c^2 so that the upper end of the holder tilts toward the wall structure and the iron is prevented from falling from the holder when the hooks e^3 are released. The holder may be secured to a wall structure by means of screws or other such securing devices which extend through the loops b^1 and c^1 .

When the holder is to be used, the heel stand of the iron is inserted into the socket at the lower end of the holder. Member E is then shifted longitudinally and the toe end of the iron swung against the upper ends of frames A and B. Member E is then released, so that the spring F will act upon it and shift it against the toe of the iron.

The invention exemplifies a sad-iron holder which is simple in construction and may be produced at a low cost.

30 The invention is not to be understood as restricted to the details set forth, since these may be modified within the scope of the appended claims, without departing from the spirit and scope of the invention.

35 Having thus described the invention, what I claim as new and desire by Letters Patent, is:

1. A holder for a sad-iron, embodying an elongated frame adapted to have the sole of 40 the iron placed thereagainst, and means for retaining the iron with the sole thereof against the frame comprising a member at one end of the frame adapted to engage the heel of the iron, a member mounted at the other end of the frame to slide longitudinally with respect to said frame and adapted to grip the toe of the iron, and a spring attached to the last mentioned member and operative to slide the same so as to 50 engage the toe of the iron and shift automatically the entire iron towards the heel engaging member.

2. A holder for a sad-iron, embodying an elongated frame adapted to have the sole of 55 the iron placed thereagainst, and means for retaining the iron with the sole against the frame comprising a member at one end of the frame adapted to engage the heel of the iron and a member slidably mounted at the other end of the frame and provided with a pair of oppositely facing hooks for gripping the toe of the iron.

3. A holder for a sad-iron having a heel stand, comprising an elongated frame, a member rigidly connected to one end of the frame

and adapted to engage the heel of the iron, said member defining an opening into which the heel stand is adapted to extend when the iron is retained by the holder, and means at the other end of the frame for pressing the iron into engagement with the heel engaging member.

4. A holder for a sad-iron having a heel stand, comprising an elongated frame, a member rigidly connected to one end of the frame and adapted to engage the heel of the iron, said member defining an opening into which the heel stand is adapted to extend when the iron is retained by the holder, a member movably connected to the other end of the frame and adapted to grip the toe of the iron, and a spring connected to said last mentioned member and applied to force the same, together with the iron, towards the heel engaging member.

5. A holder for a sad-iron, comprising an elongated frame adapted to have the sole of the iron placed thereagainst, a transversely extending member connected to one end of the frame and formed of a length of wire, 90 said wire having a portion thereof disposed at one side of the frame and adapted to form an abutment for one part of the iron, and another portion disposed at the other side of the frame and forming a supporting leg, 95 a second supporting leg at the other end of the frame, and a member movably connected to said other end of the frame, said last mentioned member being adapted to grip the opposite part of the iron and being operative 100 to hold the iron in place against the abutment.

6. A holder for a sad-iron comprising an elongated frame adapted to have the sole of the iron placed thereagainst, a transversely extending member connected to one end of the frame and formed of a length of wire, 105 said wire being bent so that it is U-shaped and being arranged so that its central portion is disposed at one side of the frame and forms an abutment for one part of the iron, and its ends are disposed at the other side of the frame and form supporting legs, a second supporting leg at the other end of the frame, and a member connected to the frame at said other end thereof and adapted 110 to grip the opposite part of the iron.

7. A holder for a sad-iron comprising a pair of frames connected together and adapted to form an elongated flat support against which the sole of the iron is adapted to be 115 placed, one of the frames being formed of a length of wire, said wire having a portion thereof bent transversely to form a supporting leg at one end of the support, a second supporting leg at the other end of the support, and means for securing the iron in place against said support.

8. A holder for a sad-iron comprising a pair of frames forming together an elongated flat support against which the sole of the iron 120

is adapted to be placed, one of said frames being formed of a length of wire, said wire having its central portion bent transversely to form a single supporting leg at one end of the support, and its ends connected to the other frame, a second supporting leg at the other end of the support, and means for securing the iron against said support.

9. A holder for a sad-iron embodying an elongated frame adapted to have the sole of the iron placed thereagainst, said frame being formed of a length of wire, a tubular member connected to the ends of the wire, and means for retaining the iron against the frame comprising a member at each end of the frame, one of the latter members being movable and having a portion thereof extending through and slidably in the tubular member.

10. A holder for a sad-iron embodying an elongated frame adapted to have the sole of the iron placed thereagainst, and means for retaining the iron against the frame comprising a member connected to one end of the frame and adapted to engage one part of the iron, a second member slidably mounted at the other end of said frame and adapted to engage another part of the iron, said second member being formed of a length of wire, the central portion of which is looped, and a spring for forcing said second member toward said first member, the spring having one end thereof connected to the looped portion of the wire and its other end anchored to the frame.

Signed at Chicago, Illinois, this 8th day of April, 1927.

RUSSELL A. WINTERS.
